[57] ABSTRACT

This invention provides an apparatus for filling a catalytic converter with a catalyst material from beneath an automobile, with the converter being mounted in the exhaust system of the automobile. The same apparatus can be used to empty the catalyst material from the converter.

SHEET 2 OF 2

CATALYTIC CONVERTER FILLING APPARATUS

Periodic maintenance of catalytic converters will be necessary, since the catalyst material used in such converters will have to be changed on a periodic basis or if it wears out, or if the catalyst is not functioning properly. Such changes should be routinely made at any local gasoline service station by one person, with a minimum of effort from underneath the automobile with the converter installed in the exhaust system.

Prior art U.S. Pat. Nos. 3,184,291 and 3,295,565 disclose apparatus for filling exhaust gas purifiers. U.S. Pat. No. 3,184,291 shows an apparatus located above the purifier to provide a gravity feed of a catalyst to the purifier, and which also draws air through the catalyst filled hopper to fluidize the catalyst to aid in the feed of the catalyst. U.S. Pat. No. 3,295,565 uses a venturi type inspirator adjacent the bottom of a catalyst feed hopper located above a purifier, to fluidize the catalyst flowing from the hopper.

Applicant's invention is a compact catalytic converter fill apparatus that can be routinely used in any local gasoline service station and easily mounted on the converter to fill the converter from underneath an automobile. The fill apparatus includes an unobstructed fill pipe that is positioned at one end on a catalyst container while the other end fits into a converter fill hole, wherein the catalyst material is pulled upwardly through the fill pipe and into the converter against the effects of gravity and without air passing through the catalyst material in the container.

Accordingly, the advantages of the invention will become apparent from the following detailed description, reference being had to the accompanying drawings of which:

FIG. 1 is a side elevational view of the preferred embodiment shown mounted on the converter in the fill position.

FIG. 2 is an enlarged close-up partial sectional view of the preferred embodiment shown in FIG. 1.

FIG. 3 is a sectional view taken along line 3—3 of FIG. 2.

FIG. 4 is a sectional view taken along line 4—4 of FIG. 2.

FIG. 5 is an enlarged close-up partial sectional view of a second embodiment of the invention in position to empty the converter.

FIG. 6 is an enlarged close-up partial sectional view of a second embodiment of the invention in position to fill the converter.

Referring to the drawings the filling apparatus includes a clamp 10 positioned on converter 12 with the converter being mounted in the exhaust system 13 of automobile 15 shown on a hoist and having the preferred embodiment of the filling apparatus in place to fill the converter. As best shown in FIG. 4, clamp 10 comprises a stationary upright arm 16 that is attached in an upright position by welding to a bottom plate 18. Upright arm 16 is generally L-shaped and is constructed so that it hooks over and rests on the top of seam weld 14. Plate 18 fits under and extends completely across the bottom of the converter and beyond both sides of the converter to hold arm 16 at one end and an over-center toggle clamp 20 at the opposite end.

Toggle clamp 20 has an adjustable positioning arm 22 mounted thereon, that fits over the center seam weld 14 in the same manner as arm 16. Arms 16 and 22 are tightened against the seam weld, by the over-

center toggle clamp 20. Clamp 10 mounts a vibrator 24 and a container securing member 26 on the bottom of the converter with one end of the securing member 26 being held adjacent the converter fill hole.

5 Vibrator 24 mounted to the bottom plate 18 is used to vibrate the converter during filling, while container securing member 26 which includes a movable arm 28, held against bottom plate 18 by spring 29, is used to retain and position the catalyst container. Spring 29 is 10 held against movable arm 28 by a spring retainer plate 30 and a bolt 32.

Movable arm 28 on securing member 26, best shown in FIG. 3, is slotted at one end as at 34 and includes a handle 36 to pull the movable arm downward away 15 from the bottom of the converter against the force of spring 29, to allow the fill pipe 42 in the catalyst container 38 to be placed in the slot 34 to secure and position the container adjacent to and within the converter fill hole 56 during filling.

20 Container 38 is generally circular in shape at its top portion and terminates in a funnel shaped end 40 having a fill pipe 42 positioned within the bottom of the funnel shaped end. The end of the fill pipe located in the funnel shaped end of the container is closed by a 25 screen 44 to prevent the catalyst material from falling out of the end as the catalyst is admitted into the fill pipe through opening 46. The other end of the fill pipe is open and extends above the container and has a collar 48 adjacent the end of the fill pipe. The fill pipe 42 30 fits into slot 34, while the collar 48 is located above the slot 34, to secure the fill pipe in a locked position within the converter. Container 38 includes a plurality of equally spaced handles 50 that are used to grip the container when placing it in position in slot 34 or which 35 can be used as legs, to set the container on when not in use.

When the catalytic material in the converter is to be replaced, the movable plate 28 is moved away from the converter by handle 36, and fill pipe 42 is placed within slot 34 and into the fill hole 56 and the handle released to secure the end of the fill pipe in the fill hole, by collar 38 being securely held between the converter and movable plate 28.

45 In operation, the catalytic material is placed in container 38 prior to the container being positioned on the converter. When the container is positioned as previously described, the aspirator 52 attached to the exhaust system by a pipe means 54 is turned on, to create a suction in the exhaust system and through the fill pipe. The suction pulls the catalyst material through the opening 46 in fill pipe 42 up through the fill pipe and into the converter 12. During the filling period, vibrator 24 is turned on, to assure complete compacting 50 and filling, because if the converter is not completely filled, the catalyst material will wear out prematurely due to a rubbing action caused by the looseness of the catalyst material. After the converter is completely full, the container is removed and the fill plug replaced in fill hole 56, and the aspirator turned off.

60 To empty the converter, the vibrator is turned on, and the container 38 is attached to member 26, with the fill pipe located to one side of the fill hole, to catch the catalyst material as it flows out of the converter. As an alternative, the fill pipe can be made removable and replaced by a plug in the bottom of the container to prevent spilling or, if desired, any type container or bucket having a handle means could be positioned on

clamp 26 or could be hand held below the fill opening.

Since the catalyst retainer slopes toward the fill hole, the catalyst will flow from the converter without any assistance other than from the vibrator, therefore the vibrator should be used to empty the converter. The catalyst material used will not readily flow out of the converter because of its make up, without the use of the vibrator. If it is desired to further speed up the emptying operation, the automobile can be tilted forward on the hoist, to provide additional slope to the catalyst retainer.

A second embodiment is shown in FIGS. 5 and 6 and includes a catalyst container 70 generally circular in shape at the top portion and terminates in a funnel shape section at the bottom portion. Fill pipe 72 is attached at the side of the container 70 and is open at the top adjacent the top of the container and also at the opposite end that is adapted to fit into the fill hole 77. Fill pipe 72 also has an opening at 75 to allow the catalyst material within container 70 to flow into the fill pipe. Hangers 74 are used to hold the container and fill pipe in position on the exhaust system 13 of the automobile. As in the first embodiment, a vibrator 76 is used to vibrate and compact the catalyst material during filling.

As shown in FIG. 5, the apparatus is being used to empty the converter with the container being positioned under fill hole 77 by hangers 74. The catalyst material flows from the converter into the container as described in the preferred embodiment. Hangers 74 are attached to the container at one end and to a collar 79 on the fill pipe at the other end.

As shown in FIG. 6, the apparatus is being used to fill the converter and in this position, an extension of the fill pipe is pulled out of the end of the fill pipe in order to make the fill pipe long enough to be positioned in the converter, and is in turn inserted into the catalyst fill hole 77. During the filling operation, only one hanger 74 is used on the container since the insert 78 is a press fit into the fill hole and will therefore hold the fill pipe stationary in the converter. However, if desired some additional holding means could be used at the end adjacent the fill hole or a threaded connector that mates with the threaded fill pipe could be used along with a locking collar to hold the threaded connector in locked position. The filling operation is the same as described in the preferred embodiment whereby the aspirator is turned on to create a suction in the exhaust system and through the open pipe 72 to cause the catalyst material to be sucked through the fill pipe and into the converter. As is readily apparent the apparatus shown in FIGS. 5 and 6 is the same apparatus, but reversed on filling and emptying.

As shown and described, the invention is a simple, compact apparatus that can be easily used by one person and easily adapted for use at any gasoline service station to empty and fill catalyst materials that will need to be replaced from time to time in the converter. The apparatus is mounted beneath the converter so as to make filling and emptying of the converter easier, due to ready access of the converter and the work area.

While the embodiments of the invention as herein disclosed constitute a preferred form, it is to be understood that other forms could be adopted.

I claim:

1. An apparatus for filling a catalytic converter with a catalyst material while the converter is mounted in an automobile exhaust system comprising: a container to

hold the catalyst material, said container adapted to be suspended beneath the converter mounted in the automobile exhaust system, an unobstructed fill pipe attached to said container and having an opening therein to permit the catalyst material to flow from said container through the opening and into said fill pipe, means to prevent the catalyst material from spilling out of said fill pipe after passing through the opening in the fill pipe, suspension means to hold said fill pipe and 10 container beneath the converter and within a fill opening in the bottom of the converter while the converter is being filled, an aspirator adapted to be connected to the exhaust system to create a suction through the exhaust system, the fill pipe, and converter to carry the 15 catalytic material from said container upwardly against the force of gravity through the fill pipe and into the converter with the aspirated air being drawn through said fill pipe without being drawn through the catalyst material in the container, and a vibrator adapted to be 20 attached to said converter to vibrate the converter as it is being filled to assure the catalytic material is compacted and the converter completely filled.

2. An apparatus for filling a catalytic converter with a catalyst material while the converter is mounted in an 25 automobile exhaust system comprising: a container to hold the catalyst material said container adapted to be suspended beneath the converter and having an enlarged upper portion that tapers into a funnel shaped lower portion that terminates in a circular opening, a fill pipe positioned within said container having one 30 end attached to the interior of the circular opening in said funnel shaped lower portion with the other end extending above said container, said fill pipe having an opening therein above the circular opening in said funnel shaped lower portion to allow the catalyst material to flow from said container through the opening and into said fill pipe, perforate means that closes off the fill pipe at the one end to prevent the catalyst material from spilling out of said fill pipe, a retaining member 35 attached to said converter by an adjustable clamp, said retaining member having a slotted end thereon to receive the other end of the fill pipe within the slotted end and which fill pipe fits into a fill hole on the converter, a collar secured on the other end of said fill pipe above the slotted end that is held against the converter adjacent the fill opening to securely hold the fill pipe in the fill hole and the container beneath the converter, an aspirator adapted to be connected to the exhaust system to create a suction through the exhaust system, 40 the converter, and the fill pipe to carry the catalyst material upward against the force of gravity through the fill pipe and into the converter from said container with the aspirated air being drawn through said fill pipe without being drawn through the catalyst material in the container, and a vibrator adapted to be attached to 45 said adjustable clamp on said converter whereby the vibrator is used to vibrate the converter during filling to assure complete filling and compacting of the catalyst material.

3. An apparatus for filling a catalytic converter with a catalyst material while the converter is mounted in an automobile exhaust system comprising: a container to hold the catalyst material having an enlarged upper portion that tapers into a funnel shaped lower portion and which terminates in an opening in the lower portion, a fill pipe having one end secured to the exterior 55 of said container along the outside of the enlarged

upper portion and also to the funnel shaped lower portion, said fill pipe having an opening therein in alignment with said opening in the lower portion of said container to allow the catalyst material to flow from said container into said fill pipe, means to secure said container and fill pipe to the exhaust system beneath the converter with the end of the fill pipe not secured to said container being inserted in a fill hole on the converter, an aspirator adapted to be connected to the exhaust system to create a suction through the exhaust

10

system, the converter, and fill pipe to draw the catalyst material upward against the effect of gravity through the fill pipe and into the converter from said container with the aspirated air being drawn through said fill pipe without being drawn through the catalyst material in the container, and a vibrator adapted to be attached to said converter whereby the vibrator is used to vibrate the converter during filling to assure complete filling and compacting of the catalytic material.
